UNITED STATES PATENT OFFICE.

EDWIN W. WEBB AND FRANKLIN L. BARBER, OF CHICAGO, ILLINOIS, ASSIGNEES TO
STANDARD CAR TRUCK COMPANY, OF CHICAGO, ILLINOIS, A CORPORATION OF NEW
JERSEY.

ROLLER-SEAT FOR LATERAL-MOTION TRUCKS.

1,206,391.

Specification of Letters Patent. Patented Nov. 28, 1916.

Application filed September 3, 1915. Serial No. 48,929.

To all whom it may concern:

Be it known that we, EDWIN W. WEBB and FRANKLIN L. BARBER, citizens of the United States, residing at Chicago, in the county of Cook and State of Illinois, have invented certain new and useful Improvements in Roller - Seats for Lateral - Motion Trucks; and we do hereby declare the following to be a full, clear, and exact description of the invention, such as will enable others skilled in the art to which it appertains to make and use the same.

Our invention relates to lateral motion trucks of the well known Barber type, and has for its object to provide an improved roller seat therefor. These roller seats are sometimes designated as combined spring caps and roller bases. A roller seat of this character is, for example, illustrated in the J. C. Barber Patent No. 565,421, of date, August 11th, 1896, wherein the vertically movable elements illustrated in Figs. 5 and 6 of the said patent are guided for vertical movements by the bolster columns, and are termed "spring caps," although they serve as combined spring caps and roller seats. In this specification, the said elements will be designated as roller seats. Roller seats of this character are notched, or otherwise formed so that they are provided with thrust lugs that engage the inner and outer sides of the bolster columns. These thrust lugs hold the roller seats against movements transversely of the truck, and are subjected to very considerable strains, due to the lateral movements of the car body in respect to the truck frames, so that, in practice, the said lugs have very frequently been broken off. Our present invention affords a light, simple and strong construction of roller seat wherein the lugs thereof are made strong enough to resist the greatest strains to which they will ever be subjected in service.

The improved roller seat is illustrated in the accompanying drawings, wherein like characters indicate like parts throughout the several views.

Referring to the drawings, Figure 1 is a plan view of the improved roller seat; Fig. 2 is an edge elevation thereof, showing the

roller seat, however, turned into a vertical plane; Fig. 3 is a vertical section taken on the line $x^3 x^3$ of Fig. 1; Fig. 4 is a side elevation of the improved roller seat; Fig. 5 is a bottom plan view of the same; and Fig. 6 is a vertical section taken on the line $x^6 x^6$ of Fig. 5.

The body of the roller seat is indicated by the numeral 1, and on its top it is formed with diverging roller bearing surfaces 2 and 3 with raised stop flanges 3 at the ends of the said roller bearing surfaces, which latter prevent endwise displacement of the rollers, not shown. At its ends, the body 1 of the said seat is formed with large notches 4 adapted to embrace the bolster columns of the truck side frames. Otherwise stated, the said roller seat is formed at its ends with projecting thrust lugs 5 that engage the inner and outer faces of the bolster column. On its upper face, the said roller seat 1 is formed with raised flanges 6 that follow the three sides of the notches 4, and hence, extend along the inner upper portions of the said lugs 5; and on its under face, the said seat 1 is formed with corresponding depending flanges 7 that follow or form continuations of said raised flanges 6, so that the flanges 6 and 7 very greatly afford vertically extended wearing surfaces for engagement with the truck bolsters. On its under side, the said roller seat 1 is further formed with depending flanges 8 that follow the inner and outer edges thereof, and also follow the extreme outer edges of the thrust lugs 5 and 8 join integrally with the extremities of the depending flanges 7. This gives a very light and strong construction and carries the reinforcement to the very ends of the thrust lugs 5.

A roller seat construction, as described, is well adapted to be made out of malleable casting, steel casting, or drop forging.

What we claim is:

A roller seat, for the lateral motion device of a car truck, formed on one face with roller bearing surfaces and provided at its ends with column-engaging notches, and thrust lugs at the extremities of said notches, said seat, on its side with the roller bearing

surfaces, having flanges that follow the three sides of said column-engaging notches and on its other side having an endless marginal flange that follows the outer side edges 5 thereof, the margins of said thrust lugs and the three sides of said column-engaging notches.

In testimony whereof we affix our signatures in presence of two witnesses.

EDWIN W. WEBB.
FRANKLIN L. BARBER.

Witnesses:

LEO W. BARBER,
ROY ANDERSON.
